UNITED STATES PATENT OFFICE.

WILLIAM STOKES AND ROBERT HUDSON, OF STOCKBROOK MILLS, ENGLAND.

ELASTIC WOVEN FABRIC.

SPECIFICATION forming part of Letters Patent No. 495,762, dated April 18, 1893.

Application filed August 21, 1891. Serial No. 403,326. (Specimens.) Patented in England January 21, 1885, No. 877.

To all whom it may concern:

Be it known that we, WILLIAM STOKES and ROBERT HUDSON, subjects of the Queen of Great Britain, and residents of Stockbrook Mills, Derby, England, have invented certain new and useful Improvements in Elastic Woven Fabrics, (patented in England January 21, 1885, No. 877,) of which the following is a full, clear, and exact description.

10 This invention has for its object improvements in the manufacture of elastic webs suitable for insertion as gores or gussets in clothing, boots and shoes, and other articles requiring elasticity.

15 Our invention has for its object the production of elastic web with a perfectly smooth diagonal cloth or satin face, enabling a large quantity of material to be thrown on the face thereby making it durable and smooth. The 20 face can be made in silk, schappe, mohair, cotton, wool, or similar fibers.

In manufacturing our improved elastic web we may use harness shafts, worked by cams or tappets on a revolving barrel, or shaft, or 25 we can use a Jacquard machine, or other suitable method of operating our shafts and shuttles, as will be understood.

30 In the accompanying drawings forming part of this specification, Figure 1, is a vertical sectional elevation of so much of a loom as is necessary to illustrate the manufacture of our improved web. Fig. 2, is a diagram, illustrating the diagonal character of the face as shown by the position of the several binders. 35 Fig. 3, is a longitudinal section, showing the position of the various binder or warp threads in the fabric, (the stuffing warp being omitted) at each pick or chute of the weft, and the arrangement of the wefts. Fig. 4, is a diagrammatic plan view of the threads representing the surface of the fabric.

40 In practicing our method of weaving the improved web by the use of tappets or cams on a revolving shaft or barrel to operate the harness, we use six harness shafts for the binder threads. The section in Fig. 1, is taken as the shuttles P P' are going past the center of the front of the sley O, and passes through the center of the shuttles and binder 45 shafts A², B², C², D², E², F². The view also shows the position of these various binder shafts and also that of the tappets A, B, C, D,

E, F, operating them when the tappet A is perpendicular. The position of the levers A', B', C', is also shown, but levers D', E', F', in this position are not seen, as they are necessarily behind lever C'.

5 K L are the edge wire shafts. G, H, I, the rubber warp shafts.

J is the stuffing shaft.

M is the rubber. N the warp. O the sley.

P the top shuttle, P' the bottom shuttle.

Q is the fabric issuing from the loom. R 60 cords for the weights.

As shown, tappets are used to operate the 65 binder shafts and are set on a spindle 40 as in Fig. 1.

The levers A', &c., for operating the harness or binder shafts A², &c., are fitted with friction rollers as shown for the tappets A, &c., 70 to ride on. When harness or binder shaft A² is at the bottom, the shuttle P' goes over the warps carried by it one chute. This shaft A² then rises to the center and the shuttle P goes over the warps carried by it twice. The shaft 75 A² then rises to the top and stands still while the shuttle P goes under the warps carried by it once, the shaft A² then falls to the center and the shuttle P goes over the warps carried by it twice and afterward the shaft A² falls 80 to the bottom and the shuttle P' goes over the warps carried by it once. The movement of shuttle P thus makes the face of the fabric and the corresponding shuttle P' the back. Shafts B², C², D², E², F², repeat the above operation in consecutive order. By this action 85 of the binder shafts and shuttles such satin or smooth face and back are produced, by the weft thrown up by the binders. The stuffing shaft J is placed as a fixture in the center as 90 shown, but the stuffer warp may be omitted.

In the drawings Fig. 1, the binder shaft A² is shown at the top, the shuttle P is going past the center of the sley O. One edge-wire shaft L is then at the center and the other K down. Harness or binder shaft B² is down while shafts 95 C², D², E², F², are at the center as is also shaft I, and necessarily the fixed stuffing shaft J. The shafts G H are down. The next movement of the loom will at once be apparent to 100 any practical weaver in reference to the foregoing description of the method of weaving the web with our smooth face and back.

In Fig. 2 the diagonal character of the face

is shown by the position of the binders lettered A² B² C² D² E² and F²; G, H, and I, being the rubber shafts. In the longitudinal section Fig. 3, the binder or warp threads are 5 indicated by the letters A² B² C² D² E² F², the numbers 1, 2, 3, 4, 5, 6, denote the six picks, the position of the various warp threads at each pick being clearly shown.

We have not shown the application of Jac- 10 quard or other equivalent mechanism to the tappets shown as such machinery, as that now in use can be adapted for the purposes of our invention by any intelligent weaver.

By reference to Figs. 3 and 4, and especially 15 in the latter figure, where the small semi-circles 20 represent the points at which the warp threads pass over and outside of the back weft threads, it will be noticed that the pair of threads A², B², as they lie in the fabric are 20 oppositely arranged, that is to say, the thread A² passes out over the face weft while the thread B² passes out over the back weft thread directly opposite, they then pass into the middle between two weft threads on the face and 25 back respectively, and then the thread B² passes out over a face weft while at the same point the thread A² passes out over the opposite back weft after which both threads pass into the middle again and then pass as before. 30 The next pair of threads C², D² lying respect- ively to the right and adjacent to the threads A² B² pass in the same manner but while the first pair mentioned, A², B² pass out over the first weft thread, Figs. 3 and 4, on the face 35 and back respectively, the second pair C², D²

pass out over the next weft threads on the face and back, numbered 2. The third pair of warp threads, E² F² pass in the same manner, but are bound by the third weft threads.

Having thus described our invention, what 40 we claim is—

A fabric consisting of central rubbers, a series of face wefts, and a series of back wefts, a series of six warp threads arranged in pairs A² B²; C² D²; and E² F², the thread 45 A² of the first pair passing out over the face weft 1 and the thread B² passing out over the opposite back weft 1 both threads then passing in the middle between two face weft threads 2 and 3 and two back wefts 2 50 and 3, the thread A² then passing out over a back weft 4 while the companion thread B² passes out over a face weft 4; the second pair of warp threads C² D² passing in the same manner with relation to the next weft threads 55 2, and the third pair of warp threads E² F² also passing in a similar manner with relation to the third weft threads 3, each weft thread being floated over the rubbers and all the threads of the several pairs excepting the 60 one which binds it, substantially as described.

In witness whereof we have hereunto set our hands in presence of two witnesses.

WILLIAM STOKES.
ROBERT HUDSON.
